ADAPTER

Jacob Rudin, Paterson, N. J., assignor to Western
Electric Company, Incorporated, New York,
N. Y., a corporation of New York

Application February 8, 1939, Serial No. 255,199

2 Claims. (Cl. 173—334)

This invention relates to an adapter, and more particularly to an electrical attachment plug and receptacle wherein accurate polarity is assured.

In connecting electrical devices in electrical circuits it is frequently desirable and oftentimes necessary that the correct polarity be assured. Two most commonly used types of attachment plug and receptacle for accomplishing this purpose are those of the radial type, having pairs of terminals and receiving sockets, with one of each pair being disposed at right angles relative to the other, and those of the parallel type, having pairs of terminals and receiving sockets with one of each pair being wider than the other so that the terminals of a plug can be connected only in one way to an electrical circuit through its receptacle. However, difficulty frequently arises when an electrical device is equipped with a plug having terminals of one type when the only receptacles available are those of the other type.

An object of the invention is to provide a simple, efficient and practical adapter for conditioning a receptacle of one type to accommodate an attachment plug of another type.

With this and other objects in view, the invention comprises an adapter having interconnected body members of insulating material housing spring contacts joined to terminals of one type and electrically engageable by terminals of another type, the body of this being so constructed that in assembly and in use the correct polarity is assured.

Other objects and advantages will be apparent from the following detailed description when taken in conjunction with the accompanying drawing, wherein—

Fig. 1 is a perspective view of the adapter, one body member thereof being shown removed from the other;

Fig. 2 is a plan view of the adapter, and

Fig. 3 is an end elevational view of the adapter.

Referring now to the drawing, particularly Fig. 1, body members 10 and 11 are shown grooved to receive contact springs 12 and 13 connected electrically to terminals 14 and 15, respectively. In this embodiment of the invention terminals 14 and 15 are of the radial type, one being positioned at right angles with respect to the other and receivable in a receptacle of the type shown at 16 in Fig. 1.

Referring now to the formation of the body member 10, it will be observed that the inner surface 17 is constructed to fit flush with the inner surface 18 of the body member 11. A rectangular projecting central portion 20 integral with the body 10 and terminating short of the ends thereof extends above the surface 17 and serves as an interlocking member with the body member 11, as will hereinafter be described. The side walls of the projection 20 continue into the body mem-

ber to form inner walls of elongate grooves 21 or recesses which partially house the spring contacts 12 and 13. Recesses 24, 25, 26 and 27 are formed in the body portion, connecting the recesses 21 with the ends of the body portion and cooperating with similar recesses formed in the body member 11 to form terminal receiving apertures varying in size. The recesses 24 to 26 inclusive are so formed that their inner walls lie in planes with the adjacent walls of the projection 20 and the inner walls of their respective recess 21. The opposite parallel walls of these recesses are positioned approximately half the distance between their respective parallel walls and the outer walls of the recesses 21, forming offset portions for the curved ends of the terminals 14 and 15. Therefore, the terminals 28 of an attachment plug 29, receivable in the recesses 24 and 26 or in the recesses 25 and 27, will be guided between the inner walls of the recesses 21 adjacent the projection 20 and the transversely projecting resilient inner ends 30 of the contacts 12 and 13. The terminals 14 and 15 as well as the terminals 28 may be defined as non-reversible terminals as well as terminals of different types, as they can be inserted in their respective terminal receiving apertures in only one way and cannot be inserted therein in reverse order.

In connecting the contacts 12 and 13 to their respective terminals 14 and 15 integral portions 32 are provided, these portions extending upwardly as shown in Fig. 1 and inwardly at right angles to positions where they are connected, in any suitable manner, such as by riveting, to their respective terminals.

Referring now to the body member 11, it will be observed that this member has a general recess 35, the width of which is equal to the distance between the outer walls of the recesses 21 and the length of which is equal to the length of these recesses. The depth of the recess 35 at the side walls of the body member terminates at walls 36, which form covers for the recesses 21 in the body member 10 and complete the spaces 45 in the adapter for the housing of the contacts. The walls 36, however, are cut away, at 37, for receiving the integral portions 32 of the contacts. Between the walls 36 and the ends of the body member 11 another recess is formed, indicated at 38, this recess being similar in contour to the rectangular projection 20 of the member 10, and is designed to receive this member and cooperate therewith in forming an interlocking association between the members. Apertures 40 and 41 are 55 provided for the projection of the terminals 14 and 15, respectively, therethrough. Recesses 240, 250, 260 and 270, similar in contour to their respective recesses 24, 25, 26 and 27, cooperate therewith in completing the terminal receiving apertures. By viewing these apertures in assem-

bly, attention being directed to Fig. 3, it will be observed that the apertures formed by the recesses 24—240 and 25—250 are smaller in their vertical dimensions than the apertures formed by the recesses 26—260 and 27—270.

The body members 10 and 11 are secured together by a single element, such as a bolt 45, having its head embedded in a countersunk portion of the body member 10 and its nut embedded in a countersunk portion of the body member 11.

One important feature of the invention is the assembly of the contacts, terminals and body members to form a complete adapter and assure the correct polarity when included in an electrical circuit. The correct polarity is assured in the assembly of these elements first, by providing an interlocking of the elements so that they may be secured together by but a single connecting element such as a bolt, second, spacing the terminals to accommodate the positioning of this connecting element near the center of the members 10 and 11, and third, positioning the apertures for the element off center to make it impossible to secure the members together unless they are properly assembled. The apertures for the bolt, therefore, are positioned a slight distance to one side of the center line of the members, a distance sufficient to position the bolt receiving apertures in each member out of alignment should the members 10 and 11 be incorrectly assembled. The interlocking of the members, particularly the reception of the projection 20 in its recess 38, assures a durable and rigid structure requiring but a single element or bolt to secure the elements together. Therefore, in assembly the correct polarity is assured. By assuring the correct polarity in assembly the correct polarity is assured in use by the association of the recesses 24 to 26 inclusive of the body member 10 with their respective recesses of the body member 11 to form in each end of the adapter a narrow aperture to receive a similarly narrow terminal of the attachment plug 29 having terminals of a parallel type in electrical connection with the contact 12, whereas wider apertures will be formed in the ends of the adapter to receive wider terminals in electrical engagement with the contact 13. The difference in the dimensions of the apertures in the adapter is such that the terminals of the parallel type of an attachment plug may be connected only to their respective contacts 12 and 13 and it is impossible for the wider terminal to be inserted into electrical engagement with the contact 12, thus preventing electrical engagement of the narrower terminal with the contact 13.

Another important feature of the invention lies in the positioning of the center line of the terminals 14 and 15 at one side of the parallel center line of the body members and the bolt securing the body members together. By so positioning the terminals they may be formed identical in construction and may be secured to contact springs which are also identical in construction. The radial type of terminal, such as the terminals 14 and 15, are positioned one at right angles with respect to the other, and if these terminals were placed with their center line in the same plane as the center line of the body members, either the contact springs or the terminals or both would have to be made differing in dimensions, doubling the cost of manufacture.

Still another important feature of the invention is the formation of the body members, par-

ticularly the body member 10, having the projecting central portion 20, the side surfaces of which lie in the same plane as the inner walls of the recesses forming the terminal receiving apertures so as to assure positive electrical engagement of the terminals of the attachment plug with the contact springs. Ofttimes terminals of an attachment plug become bent toward each other or become loose in their mounting, 5 which conditions might render the attachment plug ineffective for electrical contact with the contact springs if no means were provided to assure proper spacing of the terminals of the attachment plug. The walls of the recesses 10 forming the terminal receiving apertures and the walls of the portion 20 assure the proper spacing of the terminals at all times.

The embodiment of the invention shown and described illustrates an adapter having terminals of the radial type and a receptacle receiving terminal of the parallel type. Therefore, the adapter, as illustrated in this embodiment of the invention, conditions a receptacle of the radial type for use with an attachment plug having terminals of the parallel type. An operator of a machine, for example, a portable machine electrically operated and having an attachment plug with terminals of the parallel type, may carry an adapter of this type for use when a receptacle of the parallel type is not accessible. By the aid of the adapter of the type illustrated in this embodiment the machine may be readily connected in the electrical circuit and the operator will be assured of the proper polarity.

Another embodiment of the invention which is not shown in the drawing but which may be readily understood after a careful consideration of the first embodiment of the invention, consists of an adapter having terminals of the parallel type and a receptacle conditioned to receive terminals of the radial type. With such an adapter it is possible to condition a receptacle of the parallel type to include in the circuit therewith terminals of the radial type.

The embodiments of the invention herein disclosed are illustrative only and may be widely modified and departed from in many ways without departing from the spirit and scope of the invention as pointed out in and limited only by the appended claims.

What is claimed is:

1. A portable adapter for conditioning a receptacle in an electrical circuit adapted to receive only one type of non-rotatable non-reversible terminals to include in the circuit terminals of an attachment plug of a different type, said adapter comprising non-rotatable and non-reversible terminals of the type receivable in the receptacle, and a receptacle associated with the terminals and formed to receive non-reversible attachment plug terminals of the other type.

2. A portable adapter for conditioning a receptacle in an electrical circuit adapted to receive only one type of non-rotatable non-reversible terminals to include in the circuit terminals of an attachment plug of a different type, said adapter comprising non-rotatable and non-reversible terminals of the type receivable in the receptacle, contacts electrically connected thereto, and interlocked body members formed to house the contacts and to receive non-reversible attachment plug terminals of the other type each in electrical engagement with only a certain one of the contacts.

JACOB RUDIN.
